SPOON OR SIMILAR ARTICLE OF FLATWARE

Walter T. Harada, San Francisco, Calif.

Application March 10, 1954, Serial No. 29,459

Term of patent 14 years

(Cl. D54—12)

To all whom it may concern:

Be it known that I, Walter T. Harada, a citizen of the United States and a resident of San Francisco, California, have invented a new, original, and ornamental Design for a Spoon or Similar Article of Flatware, of which the following is a specification, reference being had to the accompanying drawing, forming a part hereof.

Fig. 1 is a top plan view of a spoon or similar article of flatware showing my new design.

Fig. 2 is a side elevational view thereof.

Fig. 3 is a bottom plan view thereof.

Fig. 4 is an enlarged sectional view thereof taken along the line 4—4 of Fig. 1.

Fig. 5 is an enlarged fragmentary perspective view of the end portion thereof.

The essential features of my invention reside in the portions shown in full lines.

I claim:

The ornamental design for a spoon or similar article of flatware, substantially as shown and described.
